UNITED STATES PATENT OFFICE.

LEA PUSEY, OF WILMINGTON, DELAWARE.

APPARATUS FOR SUBDIVIDING BLOCKS OF ICE.

SPECIFICATION forming part of Letters Patent No. 530,127, dated December 4, 1894.

Application filed December 21, 1891. Serial No. 415,706. (No model.)

To all whom it may concern:

Be it known that I, LEA PUSEY, a citizen of the United States, residing at the city of Wilmington, in the county of New Castle and State of Delaware, have invented certain new and useful Improvements in Methods of and Apparatus for Subdividing Blocks of Ice, of which the following is a full, clear, and exact description, reference being had to the accompanying drawings, of which—

Figure 1 is a perspective view of the apparatus as being applied to a block of ice. Fig. 2 is an enlarged section, as on the line *x* or *y* of Fig. 1.

The object of this invention is to provide means for readily dividing up large blocks of ice, (such as those made artificially,) into small blocks; and the device or apparatus which I use for the purpose consists of what I term a "melting frame," composed of a series of pipes communicating by means of a flexible or yielding connection, such as india rubber hose, with a pipe leading into a boiler containing steam or hot water. These pipes are arranged in the said frame according to the size and shape of the cake or block of ice to be divided, and to the size of the smaller blocks into which it is to be sub-divided, and upon the device being placed upon the large block and the steam or hot water allowed to pass through the pipes, the contiguous ice becomes melted, the pipes making their way rapidly through the same, and thus severing the cake into blocks clear cut and of uniform size.

Reference being had to the annexed drawings, which represent that form of the invention I have found most efficient and desirable, *A* is a rectangular frame, the length of which is about equal to or greater than that of the ice-block to be divided. One side of this frame is composed preferably of a bar of wood or metal *a*, while the other side is composed of a tube *a'*, usually gas or water pipe, which is rigidly connected with the side *a* by means of tubular end pieces *a*². The tube *a'* is provided with an inlet *a*³ at one end to which is attached a flexible coupling tube, such as india rubber hose *B*, the other end of which connects, or is adapted to connect, with a pipe leading to a boiler containing steam or hot water.

C is a series of parallel vertical pipes which are connected at their upper ends with the interior of the pipe *a'*, and at their lower ends with a horizontal pipe *D*, the latter being preferably of copper because of its strength and high heat conductivity.

D' is a series of copper pipes communicating with the pipe *D*, and extending at right angles horizontally therefrom.

The copper pipes *D'* are soldered or otherwise secured to metallic reinforcing strips *d'*, which are connected with the bar *a* by brace rods *d*². The pipe *D* is likewise fastened to a similar strip *d*³.

The mode of using the melting frame is as follows: It is placed upon the block of ice, being connected with the source of steam or hot water by the flexible coupling *B*. The steam or hot water being turned on, passes into the frame pipe *a'*. Thence it courses through the pipes *C*, *D*, *D'*; and as the steam becomes condensed it passes out through the pipes *D'*, the free ends of which are left open for that purpose. The device, melting the ice in its course, rapidly sinks down through the latter until the block is entirely subdivided; or through a part of its thickness, in which latter case the small blocks may be easily separated the remaining distance by means of a wedge, or like implement.

The dimensions of the blocks depend, of course, upon the thickness of the large block, and the space covered by the series of copper pipes.

I have found the above described method and device for dividing the blocks of ice a great improvement over the plans heretofore in vogue, the latter consisting in plowing suitable grooves in the block by means of tools adapted for the purpose, or by cutting up the blocks by an ax, or otherwise breaking it up. With my method and device, however, the severing into blocks is accomplished with great ease and celerity, and the blocks are perfectly smooth and uniform in size, and present a neat, or, so to say, finished appearance.

I here remark that although the pipes *D'* may be round I prefer to make them egg-shaped in cross-section, the larger portion thereof being soldered to the reinforcing strips. The soldered edges of the copper pipes are somewhat wider than the thickness

of the said strips, and the solder is applied so as to cover and protect these edges, and thus make a smooth and uniform joint or connection. By this construction, the said strips, 5 being of less thickness than the kerf cut in the ice, by the pipes, naturally follow the latter with little or no friction. See Fig. 2. Besides the peculiar application of the solder 10 protects the upper portion of the copper pipes from the condensing action of the water.

It will be understood that I do not confine myself to the precise form of the device shown in the drawings, or to a series of pipes, as the sub-division of the large block may be made, 15 although at the expense of time, by a less number of melting pipes than I have shown, or, indeed, by a single pipe.

Having thus described my invention, I claim as new and desire to secure by Letters 20 Patent—

1. The device for subdividing blocks of ice, consisting of the combination of a main longitudinal heat conductor pipe, or member,—as a' —and a series of small transverse L-shaped conductor members—as C, d'—communicating with said main conductor, substantially as and for the purpose set forth. 25

2. In a device for subdividing blocks of ice,

the combination of a main longitudinal heat conductor pipe, or member, a small conductor 30 parallel with and beneath said main conductor, and a series of small transverse L-shaped conductors communicating with said parallel conductors, substantially as and for the purpose set forth. 35

3. In a device for subdividing blocks of ice, the combination of a main longitudinal heat conductor pipe, or member, a series of small transverse L-shaped conductors communicating therewith, and a flexible or yielding 40 conductor member attached to said main conductor, and adapted to be connected to the source of heat supply, substantially as and for the purpose set forth.

4. In a device for subdividing blocks of ice: 45 the combination of the supply pipe, the vertical pipes C communicating therewith, the horizontal pipes D, d', the end pieces a^2 , the supporting rods d^2 , and the supporting bar a .

In testimony whereof I have hereunto af- 50 fixed my signature this 1st day of October, A. D. 1891.

LEA PUSEY.
